GRINDING MACHINE

Ralph L. Bazley, Jackson Heights, N. Y., assignor
to Square D Company, Detroit, Mich., a cor-
poration of Michigan

Application October 5, 1944, Serial No. 557,260

7 Claims. (Cl. 51—122)

1

This invention relates to a grinding machine for grinding arcuate profiles on workpieces.

An object of the invention is to provide a grinding machine with means for associating a workpiece with the grinding wheel, rotating the workpiece about a desired center, and reciprocating the workpiece across the face of the wheel as it is being rotated.

Another object of the invention is to provide a grinding machine with a workpiece support mounted for rotation about a pivot with means for effecting reciprocation of said support as the work is rotated.

Other objects and features of the invention will be readily apparent to those skilled in the art from the specification and appended drawing illustrating certain preferred embodiments in which:

Figure 1 is a side elevational view of the grinding machine according to the present invention.

Figure 2 is a front elevational view of the grinding machine.

Figure 3 is a partial top plan view of the grinding machine.

Figure 4 is a partial vertical sectional view through the grinding machine.

Figure 5 is a sectional view on line V—V of Figure 4.

Figure 6 is a view similar to Figure 5, but with the work manipulating means in another position.

Figure 7 is a view similar to Figure 5, but with the view manipulating means in one limiting position of movement.

Figure 8 is a plan view of a workpiece which may be formed in the machine.

Figure 9 is a side elevational view of the workpiece of Figure 8.

The grinding machine as illustrated in the drawings comprises a table 1 upon which is supported a motor 2 and a grinding wheel 3 driven thereby through a gearing system, not shown but contained in the gear housing 4. The housing 4 supports a bracket 5 having a pair of side wings 6 in which is pivotally supported a platform 7. Upon the platform 7 is mounted a way 8 with which cooperates a slide 9. An adjusting screw 11 is threaded into the way 8 and has a double collar engagement with the slide 9 as shown more particularly in Figure 4. On the slide 9 is mounted a way 12 with which is associated a transverse slide 13. Upon the slide 13 is supported an arcuate guiding and retaining plate 14 having a notched periphery at 15 providing an overhanging portion within which is

2

disposed the notched complementary end of a plate 16 attached to the under surface of a work holder 17. Through the plate 16 and the slide 13 is a bushing 18 within which is rotatably mounted a pivot pin 19 keyed at its upper end to the work holder 17. The way 12 has a cutout portion 21 in which is disposed a link 22 keyed to the lower end of the pivot pin 19. The opposite end of the link 22 is keyed to a pin 23 reciprocal within a slot 24 in the slide 9. The link 22 is freely movable within the cutout portion 21 between the slides 9 and 13.

In the upper portion of the work holder 17 are provided seats 25 for the workpiece 26. For holding the workpiece 26 against the seats 25 there is provided locking means formed by a lever 27 carrying an adjustable work engaging stud 28 and pivoted on the work holder 17 at 29. For locking the lever 27 in place, there is provided a manually operable lever 31 pivoted on the work holder at 32 and having a pin 33 for engaging and holding the lever 27 in its locking position.

Extending from the housing 4 is a platform 34 carrying trunnions 35 within which is pivoted a shaft 36 having an operating crank 37 and carrying a cam 38 engaging an adjustable follower 39 on the platform 7. The platform 7 has an integral upwardly extending arm 41 carrying an adjustable stop 42 engaging with the head of stud 43 in the bracket 5. The slide 13 is provided with extensions 44 at its opposite sides carrying adjustable stops 45 limiting the extreme positions of the work holder 17.

In the operation of the grinding machine according to the present invention, the parts are in an inoperative, work inserting and removing, position as shown in Figure 1. The workpiece is placed upon the seats 25 and locked in position by manipulation of the lever 31. The crank 37 is then manipulated to rotate the platform 7 and the parts supported thereon into their horizontal position as shown in Figure 4. This is effected through engagement of the cam 38 with the follower 39 to effect counterclockwise rotation of the platform 7 until the stop 42 engages the head of stud 43. Thereafter, the profile is placed upon the workpiece by moving the work holder 17 through the desired angular movement.

In Figures 8 and 9, the workpiece illustrated is an optical prism and the machine is utilized to form the 180° arcuate profiles at the opposite ends of the prism. The full lines of Figure 8 represent the finished product and the dotted lines the initial blank upon which the operation

is performed. The radius of the arcuate profile is determined by adjustment of the slide 9 by means of adjusting screw 11 to move the center of rotation determined by the axis of pin 19 toward and away from the grinding wheel 3.

An important feature of applicant's invention lies in the provision of transverse movement of the workpiece as it is being rotated with respect to the grinding wheel. This is effected through the operation of the link 22, pin 23 and slot 24. As the work holder 17 is rotated about the axis of the pin 19, the link 22 rotates therewith. However, the pin 23 is mounted on the link 22 and movement of the pin 23 is limited to a rectilinear one by the slot 24. Accordingly, as pin 19 rotates it must move in a transverse direction as the pin 23 moves within the slot. This transverse movement is effected by transverse movement of the slide 13 with respect to the way 12. The transverse movement of the pin 19 which will carry the work holder and work therewith is indicated in Figures 5, 6 and 7 in which as the work holder 17 is rotated, as indicated by the arrows in a counterclockwise direction, the pin 23 will move toward the left and effect a movement of the pivot pin 19 downwardly as viewed in these figures, such movement being accompanied by movement bodily of the slide 13 and the parts supported thereon. This transverse movement of the work as it is rotated with respect to the grinding wheel spreads the grinding operation over a large surface and avoids the formation of a groove within the wheel which would destroy its life and accuracy.

The adjustable stops 45 determine the angular movement of work holder 17. In the present instance, they are located to provide for 180° rotation of the workpiece to form the desired profile of the workpiece as shown in Figure 8.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What is claimed is:

1. In a machine for grinding an arcuate profile upon a workpiece, a grinding wheel having a radial, planar, grinding face, means for rotating said grinding wheel about an axis perpendicular to said grinding face, a slide movable parallel to said grinding face, a holder for the workpiece mounted on said slide for rotation about an axis at right angles to the direction of movement of the slide and parallel to the plane of said grinding face and spaced therefrom by the dimension of the radius of the desired arcuate profile, and means connected to said workholder for effecting reciprocation of the slide as an incident to the rotation of the workholder about its pivotal axis.

2. In a machine for grinding an arcuate profile upon a workpiece, a grinding wheel having a radial, planar, grinding face, means for rotating said grinding wheel about an axis perpendicular to said grinding face, a slide movable parallel to said grinding face, a holder for the workpiece mounted on said slide for rotation about an axis at right angles to the direction of movement of the slide and parallel to the plane of said grinding face and spaced therefrom by the dimension of the radius of the desired arcuate profile, means connected to said workholder for effecting reciprocation of the slide as an incident to the rota-

tion of the workholder about its pivotal axis, a second slide mounted for movement perpendicular to the plane of the said grinding face, means for mounting said first-mentioned slide on said second slide, and means for effecting adjusting movement of said second slide to locate said workholder pivotal axis at the desired distance from the plane of the grinding face.

3. In a machine for grinding an arcuate profile upon a workpiece, a grinding wheel having a radial, planar, grinding face, means for rotating said grinding wheel about an axis perpendicular to said grinding face, a slide movable parallel to said grinding face, a holder for the workpiece mounted on said slide for rotation about an axis at right angles to the direction of movement of the slide and parallel to the plane of said grinding face and spaced therefrom by the dimension of the radius of the desired arcuate profile, means connected to said workholder for effecting reciprocation of the slide as an incident to the rotation of the workholder about its pivotal axis, a second slide mounted for movement perpendicular to the plane of the said grinding face, means for mounting said first-mentioned slide on said second slide, means for effecting adjusting movement of said second slide to locate said workholder pivotal axis at the desired distance from the plane of the grinding face, and means for moving said slides and holder bodily out of association with said grinding wheel to facilitate the insertion and removal of the workpiece.

4. In a machine for grinding an arcuate profile upon a workpiece, a grinding wheel having a radial, planar, grinding face, means for rotating said wheel about an axis perpendicular to the plane of said grinding face, a supporting platform adjacent to said wheel, a slide on said platform movable parallel to said grinding face, a pivot pin journaled in said slide with its axis parallel to the plane of the grinding face, a workholder mounted on said pin for rotary movement relative to the slide about the axis of the pin, a part relatively stationary in the normal operation of the machine and having a slot therein disposed with its longitudinal axis transverse to the direction of movement of said slide, a guide pin in said slot, and a link interconnecting said pivot and guide pins to effect rotation of the guide pin about the axis of the pivot pin as the workholder is rotated whereby rotation of said workholder about the axis of said pivot pin is accompanied by movement of the slide and workholder bodily in a direction parallel to the plane of the grinding face.

5. In a machine for grinding an arcuate profile upon a workpiece, a grinding wheel having a radial, planar, grinding face, means for rotating said wheel about an axis perpendicular to the plane of said grinding face, a platform adjacent to said grinding wheel, a slide on said platform adjustable toward and away from the plane of said grinding face, a second slide on said first-mentioned slide movable parallel to the plane of the grinding face, a workholder pivotally mounted on said second slide for rotation about an axis at right angles to the direction of movement of the second slide and parallel to the plane of the grinding face, adjustment of said first-mentioned slide locating the axis of rotation of the workholder spaced from the plane of said grinding face by the dimension of the radius of the desired arcuate profile, and means connected to said workholder for effecting reciprocation of said second slide parallel to the plane of the grinding

face as an incident to the rotation of the workholder about its pivotal axis.

6. In a machine for grinding an arcuate profile upon a workpiece, a grinding wheel having a radial, planar, grinding face, means for rotating said wheel about an axis perpendicular to the plane of said grinding face, a platform adjacent to said grinding wheel, a slide on said platform adjustable toward and away from the plane of said grinding face, a second slide on said first-mentioned slide movable parallel to the plane of the grinding face, a workholder pivotally mounted on said second slide for rotation about an axis at right angles to the direction of movement of the second slide and parallel to the plane of the grinding face, adjustment of said first-mentioned slide locating the axis of rotation of the workholder spaced from the plane of said grinding face by the dimension of the radius of the desired arcuate profile, means connected to said workholder for effecting reciprocation of said second slide parallel to the plane of the grinding face as an incident to the rotation of the workholder about its pivotal axis, and means for bodily moving said platform to move the workpiece into and out of operative grinding relation with the grinding face.

7. In a machine for grinding an arcuate profile upon a workpiece, a grinding wheel having a radial, planar, grinding face, means for rotating said wheel about an axis perpendicular to the plane of said grinding face, a platform adjacent to said grinding wheel, a slide on said platform adjustable toward and away from the plane of said grinding face, a second slide on said first-mentioned slide movable parallel to the plane of the grinding face, a workholder pivotally mounted on said second slide for rotation about an axis parallel to the plane of the grinding face, adjustment of said first-mentioned slide locating the axis of rotation of the workholder spaced from the plane of said grinding face by the dimension

of the radius of the desired arcuate profile, means connected to said workholder for effecting reciprocation of said second slide parallel to the plane of the grinding face as an incident to the rotation of the workholder about its pivotal axis, means pivotally mounting said platform, and a manually manipulable cam for effecting movement of said platform about its pivotal mounting to move the workpiece into and out of grinding relation with said grinding face.
